(57) **CLAIM**

We claim the ornamental design for an evaporator for a humidifier as shown and described.

DESCRIPTION

FIG. 1 is a front perspective view of an evaporator for a humidifier showing our new design;

FIG. 2 is a front view thereof;

FIG. 3 is a rear view thereof;

FIG. 4 is a side view thereof;

FIG. 5 is an opposite side view thereof;

FIG. 6 is a top view thereof; and

FIG. 7 is a bottom view thereof.

The broken lines shown in the drawings illustrate portions of an evaporator for a humidifier that form no part of the claimed design.
